No. 882,956.

PATENTED MAR. 24, 1908.

W. P. NORRIS.
AUTOMATIC CUT-OFF.
APPLICATION FILED AUG. 12, 1907.

UNITED STATES PATENT OFFICE.

WILLIAM P. NORRIS, OF SISTERSVILLE, WEST VIRGINIA.

AUTOMATIC CUT-OFF.

No. 882,956.

Specification of Letters Patent. Patented March 24, 1908.

Application filed August 12, 1907. Serial No. 388,207.

To all whom it may concern:

Be it known that I, WILLIAM P. NORRIS, a citizen of the United States of America, residing at Sistersville, in the county of Tyler and State of West Virginia, have invented 5 certain new and useful Improvements in Automatic Cut-Offs, of which the following is a specification, reference being had therein to the accompanying drawing.

10 This invention relates to automatic cut-offs, especially adapted for use with oil tanks.

The primary object of this invention is to provide novel means for automatically closing the outlet of an oil tank to prevent air 15 from entering a pipe line.

A further object of the invention is to automatically close the tank outlet in case oil backs up in the tank under the pressure of oil from another higher tank in the line.

20 A still further object of the invention is to automatically operate the valve when the oil reaches any predetermined level in the tank.

The construction of the improvement will 25 be fully described hereinafter in connection with the accompanying drawing which forms a part of this specification.

In the drawing: Figure 1 is a side elevation of an oil tank broken away to show the 30 cut-off mechanism therein, Fig. 2 is a view in section on a slightly enlarged scale of the float-rod and float employed, Fig. 3 is an elevation of the valve for controlling the tank outlet and its casing, Fig. 4 is a vertical 35 section of said valve and casing, and Fig. 5 is a cross sectional view taken on the line $x-x$ of Fig. 3.

The reference numeral 1 designates a tank provided with an outlet pipe 2 extending 40 through the tank, and screwed into an internally threaded nipple 3 projecting from a casting 4 within which is guided a gate valve 5. The casing 4 and valve 5 are formed with registering ports 6 the port in the casing 4 45 extending upwardly at an angle to the handle as clearly seen in Fig. 4. The inner side of the casing is open, it being provided with guide flanges 7 between which the valve 5 is supported.

50 The valve 5 is provided with a screen 5^a covering the port thereof for preventing sticks etc. in the oil from obstructing the valve. One of the guide flanges 7 is provided with a slot 7^a the wall at the inner end 55 of which forms a stop for limiting the upward movement of the valve, said valve car-

rying a pin 7^b working within the slot 7^a of the guide flange 7.

The upper end of the valve 5 is provided with an eyelet 8 to which is loosely connected the lower end of a rod 9, the upper end of which is loosely connected to one end of a lever 10 fulcrumed on a bracket 11 suitably supported on top of the tank. The rod 9 is provided with an adjustable stop 9^a with which said fulcrumed lever 10 is adapted to engage. Upon the opposite end of the lever 10 is mounted a weight 12 preferably rectangular in form.

On the top of the tank 1 is mounted a base 70 plate 1^a upon which the bracket 11 is mounted, and which also has mounted thereon a bracket or a base 12^a. In the bracket or base 12^a is fulcrumed a lever arm 12^b, the inner end of which extends upwardly at an inclination 75 towards the weight 12 and is notched at its upper end to engage said weight. The outer end of the arm 12^b is bifurcated and provided on the upper face of the bifurcated portion with a plurality of notches or seats 13^a. 80 Supported in the bifurcated portion of said arm 12^b by means of a cross pin 13^b is a sleeve 13, a pin or pins 13^b engaging one or the other of the notches 13^a in the bifurcated portion of said arm 12^b. The sleeve 13 85 receives a rod 14 adjustable in said sleeve and held in adjusted position by means of a set screw 15.

The lower end of the rod 14 is provided with a head 16 and loosely mounted upon 90 said head is a hollow float 17 comprising a cylindrical vessel, closed at the top and bottom thereof and provided with a central tube 18, through which the rod 14 extends, thus allowing the float to freely move up and 95 down upon said rod with the raising or lowering of the liquid in the tank 1. At the top of the float is provided a tubular inlet 19 preferably closed at its upper end and formed with perforations 20 below its top. The size 100 of the float and the shape of the same will be according to the gravity of the oil in the tank, as in some localities particularly, it is of very low grade and in that case it is necessary to increase the size and shape of the float. 105

The upward movement of the float 17 upon the rod 14 is limited by an adjustable stop 21 carried by said rod adjacent to the housing 13.

The operation of the mechanism constructed as above described, is as follows: When the height of the liquid in the tank is lowered sufficiently, the float 17 rests upon the head 110

16, thus pulling downwardly upon the rod 14, 40
tilting the arm 12^b upon its fulcrum, releasing
the weight 12, and allowing said weight
through the medium of a fulcrum lever 10 to
5 elevate the rod 9 and raise the gate valve 5
and close the port 6. In case the oil backs
up into the tank through the pressure of oil
in a tank situated in a high elevation, it will
raise the float 17 until said float contacts with
10 the stop 21 where said float will be held, and
will gradually fill with oil as the oil in the
tank rises. Immediately upon the float 17
being filled with oil, it descends by gravity
and again engages the head 16, tilting the
15 fulcrumed arm 12^b, releasing the weight 12,
and elevating the rod 9 and the gate valve 5
to close the port 6. The rod 14 can be
readily adjusted vertically by means of its
set screw 15 to regulate the operations of the
20 valve with relation to the depth or quantity
of oil in the tank 1.

The novel construction of the ports 6 allows
the oil in the tank to reach as low a level as
it did before the cut-off was used, thus saving
25 the trouble and expense of lowering the tank
nipple or outlet pipe.

It is thought that the operation of my
improved automatic cut-off will be apparent
from the foregoing description taken in con-
30 nection with the drawings, and I reserve a
right to make such structural changes as are
permissible by the appended claims.

Having fully described my invention, what
I claim and desire to secure by Letters Pat-
35 ent, is:—

1. The combination with a tank having an
outlet pipe extending through the wall of the
tank, and a casing connected to the inner end
of the outlet pipe and having an inclined port

communicating with the outlet pipe, a gate 40
valve slidably-mounted in said casing and
having a port normally registering with the
port in the casing, a rod connected to the
upper end of the gate valve and extending
through the top of the tank, a bracket mount- 45
ed on the top of said tank, a lever pivotally
mounted in said bracket and engaging said
rod, a weight on said lever, a lever-arm
pivotally-mounted on the top of the tank and
engaging said weight, a float-rod suspended 50
from said lever-arm and extending into the
tank, and a float slidably-mounted on said
float-rod.

2. In combination with a tank having an
outlet pipe extending into the same, a casing 55
connected to said pipe and having a port
communicating with said pipe, and a gate
slidable in said casing provided with a port
normally registering with the port in the
casing, a rod connected to said gate and ex- 60
tending through the tank top, a weighted
lever pivotally-supported on the top of the
tank and connected to said rod, a lever-arm
pivotally-supported on the tank top and
engaging said weighted lever, the said lever- 65
arm having a bifurcated outer end, a sleeve
mounted in the bifurcated end of said lever-
arm, a float-rod adjustably-mounted in said
sleeve and extending into said tank, and a
hollow float slidable on said float-rod within 70
the tank.

In testimony whereof I affix my signature
in the presence of two witnesses.

WILLIAM P. NORRIS.

Witnesses:

WALTER S. KING,
B. L. BULLMAN.
